LUGGAGE LOCK OR SIMILAR ARTICLE

Charles S. Gehrie, Montclair, N.J., assignor to Presto Lock Co., Inc., Garfield, N.J., a corporation of New York

Filed Mar. 25, 1964, Ser. No. 79,171

Term of patent 14 years

(Cl. D50—7)

FIG. 1

FIG. 2

FIG. 3

FIG. 4

FIG. 5

FIG. 6

FIG. 7

FIG. 1 is a top plan view of a luggage lock or similar article embodying my new design;

FIG. 2 is a front elevational view shown without the hasp member;

FIG. 3 is a rear elevational view;

FIG. 4 is an end view looking toward the left end of the article shown in FIG. 2;

FIG. 5 is an end view looking toward the right end of the article shown in FIG. 2;

FIG. 6 is another front elevational view with the latch member shown in unlatched position; and

FIG. 7 is a perspective view of the hasp member with the rest of the latch removed for clarity.

I claim:

The ornamental design for a luggage lock or similar article, as shown.
